UNITED STATES PATENT OFFICE.

WILLIAM J. MOORE, OF PHILADELPHIA, PENNSYLVANIA.

MOP CLOTH.

Original application filed May 8, 1923, Serial No. 636,788. Divided and this application filed September 23, 1924. Serial No. 739,256.

To all whom it may concern:

Be it known that I, WILLIAM J. MOORE, a citizen of the United States, residing at Philadelphia, in the county of Philadelphia and State of Pennsylvania, have invented 5 certain new and useful Improvements in Mop Cloths, of which the following is a specification.

My invention relates to mop-cloths and 10 its objects are to provide a mop-cloth of the strand type in which the strands will be so firmly held that they cannot become loose and to provide a mop-cloth of greater durability than those now in use.

15 These objects, and other advantageous ends which will be described hereinafter, I attain in the following manner, reference being had to the accompanying drawing in which—

20 Figure 1 is a plan view of the strands of the mop-cloth showing a reinforcing band to be applied to the strands,

Figure 2 a plan view showing the band applied to the strands,

25 Figure 3 a section through the reinforcing band, and

Figure 4 a view in elevation showing the completed mop-cloth applied to a mop-holder.

30 This application is a division of my application, Serial No. 636,788 filed May 8, 1923, for mops.

The numeral 1 indicates the strands of liquid absorbing material which constitute 35 the body of the mop-cloth, 2 a reinforcing core extending laterally of the strands midway of their length, 3 a reinforcing band which embraces the strands midway of their length and which encloses the core when 40 folded on its central longitudinal line, 4 and 5 rows of stitching by which the reinforcing band is secured to the strands, 6 rows of stitching by which the band is secured in its folded position, 7 eyelets by which the 45 mop-cloth may be secured to a mop-holder, 8 a mop-holder and 9 hooks adapted to take through the eyelets and secure the mop-cloth to the mop-holder.

50 The mop-cloth is constructed by laying a series of liquid absorbing strands upon the reinforcing band, folding the reinforcing band over the strands midway of their length so that it will completely surround

the strands, securing the band to the strands by the lines of stitching 4 and 5, placing 55 the reinforcing core on the band upon its central longitudinal line, then folding the reinforcing band on the core, and securing the folded sides of the band to each other to hold the core in position by lines of stitching 60 6. That part of the mop which includes the band is further reinforced by the eyelets which pass through both sides of the band.

In use the strands of the mop are subjected 65 to pulling strains which, in the absence of a core, would be exerted upon the stitches. The core serves as a bearing and relieves the stitching of part of the strain.

The mop-cloths are designed for use in 70 pairs, thus dispensing with need for a large mop-cloth and facilitating their being cleansed. The reversible feature of the individual mop-cloths increases their durability.

75 While I have described my invention as taking a particular form, it will be understood that the various parts may be changed without departing from the spirit thereof, and hence I do not limit myself to the 80 precise construction set forth, but consider that I am at liberty to make such changes and alterations as fairly come within the scope of the appended claim.

Having thus described my invention, what 85 I claim as new and desire to secure by Letters Patent is:—

A mop-cloth comprising strands; a flexible band embracing the strands midway of their length, said band being secured to said 90 strands by rows of stitching along the edges of said band and by two rows of stitching extending parallel to each other through the center of said band and strands; a core positioned between said central parallel rows of 95 stitching, said band and strands being folded over said core; a row of stitching extending through said folded band and strands adjacent said core; a row of stitching extending through said band and strands 100 adjacent the edges of said band; and eyelets extending through said band and strands between said last-mentioned rows of stitching.

In testimony whereof I have signed my name to this specification.

WILLIAM J. MOORE.
